UNITED STATES PATENT OFFICE.

CHARLES E. WAREAM, OF NORWOOD, OHIO, ASSIGNOR TO THE AMERICAN LAUNDRY MACHINERY COMPANY, OF NORWOOD, OHIO, A CORPORATION OF OHIO.

COLLAR SHAPER.

Application filed October 25, 1919. Serial No. 333,227.

To all whom it may concern:

Be it known that I, CHARLES E. WAREAM, a citizen of the United States, residing at Norwood, in the county of Hamilton and State of Ohio, have invented certain new and useful Improvements in Collar Shapers, of which the following is a specification.

This invention relates to collar shapers, and more particularly to the heating means therefor.

The object of the invention is to provide a collar shaper including a movable or adjustable ironing member which is heated in its several positions by contact with a heat conducting or heat radiating member held in relatively stationary position, thereby to simplify the manner of supplying heat to the ironing member. More specifically the object of the invention is to provide an improved collar shaper heated electrically by a resistance element mounted in a relatively stationary member from which heat is conducted by radiation to the ironing member.

Further objects of the invention are in part obvious and in part will appear more in detail hereinafter.

In the drawings, which represent one suitable embodiment of the invention, Fig. 1 is a sectional elevation on the line 1—1, Fig. 2, the ironing members being shown in ironing position; Fig. 2 is a sectional plan view on the line 2—2, Fig. 1; Fig. 3 is a detail sectional elevation, on a larger scale, from the right in Fig. 1, of the heating element and its holder; Fig. 4 is a sectional plan view of the heating element, on the line 4—4, Fig. 3; and Fig. 5 is a sectional plan view on the line 5—5, Fig. 1, the ironing members being shown in dotted lines.

The collar shaper shown in the drawings comprises a suitable base 1 designed for attachment to a stationary support, such as a table, shelf or the like. Said base has a depending hollow post member 2 provided on its lower end with a stop lug 3. In the post is located a vertically slideable tubular member 4 provided at its upper end with a frame 5 supporting an annularly extending collar mold or form 6. Frame 5 is provided with a depending bolt 7 passing through an opening in the base 1 and whose head 8 limits upward movement of the collar mold. The mold is yieldingly pressed upwardly by a compression spring 9 surrounding a central shaft 10, the lower end of said spring abut-

ting a collar 11 of said shaft and its upper end a thimble 12 adjustably threaded into the tube 4 and locked in adjusted position by a nut 13. The pressure of said spring can be adjusted by adjustment of the thimble, as will be readily understood.

The central shaft 10 supports an ironing member which cooperates with the collar mold. Said shaft is freely rotatable in the thimble 12 and in a bearing in the lower end of the post 2. Shaft 10 is also provided with a collar 14 carrying a stop member 15 adapted to engage the lug 3 and limit rotating movement of said shaft. At its upper end the shaft supports a hollow T-shaped member 16 whose end portions are of cylindrical form and serve as trunnions to carry a bracket member 17. Said bracket member has turning motion on a horizontal axis about said trunnions and also has longitudinal sliding movement limited by the shoulders 16^a to permit the ironing member to accommodate itself to the collar mold, as will be readily understood. At one end said bracket is provided with a lower stop member 18, its upper portion carrying a pair of ears 19 between which is pivoted the latch 20, one arm 21 of which is connected by a link 22 to an upper stop lug 23 on an operating arm 24 provided with a handle 25. Said arm 24 is also provided with a lower stop lug 26 and is pivoted on a shaft 27 extending between two ears 28 on the ironing member 29 which in turn is pivotally connected by the bolts 30 to the forward portion of the bracket 17.

The inner surface, to wit, that surface nearest to the axis of shaft 10, of the ironing member 29 is curved to cylindrical form around a horizontal axis through the bolts 30. This surface contacts with the outer cylindrical surface of a heat conducting member 31 which is suitably secured, such as by screws, to the outer portion of a heating element supporting member 32 secured to or forming a portion of a hollow shaft 33 lying within the cavity of member 16 and forced outwardly or toward the ironing member 29 by the compression spring 34 in a cavity lying between members 31 and 32. Located in the cavity of member 31 is an electrical heat resistance element 35 of common form, current for which is supplied by the wires 36 extending through the central passages in the hollow members 10, 16 and 33. These wires

pass through an insulating thimble 37 at the lower end of the shaft 10 and to a suitably controlled switch 38 mounted at a convenient point on the base and connected to the usual current leads.

Fig. 1 shows the parts in ironing position. Handle 25 has been pressed downwardly to bring the ironing member 29 into engagement with a collar supported on the 10 mold 6, the downward motion being continued until the spring 9 has been pressed sufficiently to enable the latch 20 to drop into the position shown, namely into engaging or locking relation with the upper inner 15 portion of the ironing member. In this position dog 26 also engages the ironing member so that the handle 24 becomes in effect a solid part of the ironing member and the collar may be ironed by merely rotating the parts around the central vertical axis. If the switch 38 is turned on current is supplied to the resistance element 35 which heats the conducting member 31, the latter in turn radiating its heat to the ironer 20 25 30 35 40 45 50 55 60 65 70 75 80 85 90 95 100 105 110 115 120 125 130

29. Preferably the resistance element 35 is constructed in such manner or provided with any well known form of thermostatically controlled switch so that it will heat the parts only to a given temperature to thereby avoid scorching the collar. When the collar is ironed the handle 25 is lifted. The first motion releases the latch 20 after which the iron 29 is itself raised, while the heating member remains in the same horizontal plane. However, the spring 34 always maintains the pressure contact between the members 31 and 29 so that in all positions of the ironing member heat is radiated thereto from the heating element.

40. While the ironing member is movable the circuits for producing heat and the arrangement for transmitting the same to the ironing member are greatly simplified, thereby reducing the initial cost and the cost of maintenance. All circuit wires may be covered with asbestos, if desired.

What I claim is:—

1. A collar shaper, comprising a collar mold member and an ironing member movable one along the other for the ironing operation, and a heating member mounted separately from and held yieldingly in contact with said ironing member for heating the same.

55. 2. A collar shaper, comprising a collar mold member and an ironing member movable one along the other for the ironing operation, and a heating member, said ironing member also having movement independently of said heating member toward and from the mold member, and said heating member lying closely adjacent to said ironing member in all of its several positions for heating the same.

65. 3. A collar shaper, comprising a collar

mold member and an ironing member movable one along the other for the ironing operation, and a heating member, said ironing member also having movement independently of said heating member toward and from the mold member, said heating member being held in yielding contact with said ironing member in all of its several positions for heating the same.

4. A collar shaper, comprising a collar mold member and an ironing member movable one along the other for the ironing operation, said ironing member also having swinging movement toward and from the mold member, and a heating member having its surface opposite said ironing member curved around the axis of swinging movement of said ironing member as a center and lying closely adjacent to said ironing member in all of its several positions for heating the same.

5. A collar shaper, comprising a collar mold member, an ironing member rotatable around an axis and movable along said mold member for the ironing operation, said ironing member also having swinging movement toward and from the mold member, and a heating member having a curved surface lying closely adjacent to said ironing member and rotatable around said axis with said ironing member but relatively stationary as regards swinging movement of the latter for heating the same.

6. A collar shaper, comprising a collar mold member, an ironing member rotatable around an axis and movable along said mold member for the ironing operation, said ironing member also having swinging movement toward and from the mold member, and a heating member rotatable around said axis with said ironing member but relatively stationary as regards swinging movement of the latter for heating the same, said heating and ironing members contacting along surfaces curved around the axis of swinging movement of the ironing member as a center.

7. A collar shaper, comprising a collar mold member, an ironing member rotatable around an axis and movable along said mold member for the ironing operation, said ironing member also having swinging movement toward and from the mold member, a heating member rotatable around said axis with said ironing member but relatively stationary as regards swinging movement of the latter for heating the same, said heating and ironing members contacting along surfaces curved around the axis of swinging movement of the ironing member, and yielding means for holding said heating and ironing members in contact along said surfaces.

8. A collar shaper, comprising a collar mold member and an ironing member mov-

able one along the other for the ironing operation, said ironing member having also movement transversely of said collar mold member so as to permit said iron to accommodate itself to said collar mold member for proper engagement of the collar therebetween, and a heating member mounted so as to maintain proper heating relation to said ironing member throughout its transverse movement.

9. A collar shaper, comprising a collar mold member and an ironing member movable one along the other for the ironing op-

eration, said ironing member having also movement transversely of said collar mold member so as to permit said iron to accommodate itself to said collar mold member for proper engagement of the collar therebetween, and a movably mounted heating member together with yielding means for holding the same in proper heating relation to said ironing member throughout its transverse movement.

In testimony whereof I affix my signature.

CHARLES E. WAREAM.
